A. W. Hall

United States Patent Office.

A. W. HALL, OF NEW YORK, N. Y.

Letters Patent No. 67,044, dated July 23, 1867.

IMPROVED DOOR-FASTENING AND KNIFE.

The Schedule referred to in these Letters Patent and making part of the same.

TO ALL WHOM IT MAY CONCERN:

Be it known that I, A. W. HALL, of the city, county, and State of New York, have invented a certain new and useful Combined Pocket-Knife and Door-Fastener, of which the following is a full, clear, and exact description, reference being had to the accompanying drawing forming part of this specification, and in which—

Figure 1 represents a side view of the device in its closed condition.

Figure 2, a back view of the same, and

Figure 3 a view thereof in its open condition as a door-fastener, and as applied to secure a door against being opened.

Like letters indicate like parts throughout the several figures.

The nature of my invention consists in a combination with a pocket-knife, so as to form but the one device, of a gimlet or taper screw, so arranged as that when thrown open the knife may not only be used as a handle to turn the screw, which being taper is free to enter without previous boring, but is made to form a button across the door and its jamb on entering the screw into either.

Referring to the accompanying drawing, *a a* represent the sides of a pocket-knife, of which *b* is the back or knife-springs, and *c* the blades. The sides *a a* are shown extended at the back, so as to form cheeks to receive within them a gimlet or taper screw, *d*, pivoted to the sides or cheeks as at *e*, and, which may be shut down so as to lie within said sides or cheeks, as represented in figs. 1 and 2, or may be extended as in fig. 1, where it is represented as entered within the jamb *f* of a door, *g*, or it may be screwed into the door, accordingly as the latter opens inwards or outwards, the knife-handle serving as a button to cross the door and jamb as well as a handle to enter or withdraw the screw, which is preferably situated in the centre of said handle relatively to its length, to equalize the leverage on opposite sides of the screw and steady the working of it. When shut down said screw offers no obstruction to carriage of the knife in the pocket, and presents no interference with the blades when the device is designed to be used only as a knife. Furthermore, such screw being of a gimlet or taper form, no previous boring is necessary for its entry in the door or jamb.

In no respect does this door-fastener and knife combined resemble cork-screw and other combined knife-attachments as previously used, as such have never been constructed or adapted to answer as a door-fastener, as here shown and described, while other door-fasteners, employing screws, have usually required separate drilling or boring before the screw could be applied, or have been of themselves a separate device, not combined with a knife, which latter arrangement is not simply a matter of economy as dispensing with a distinct handle, but a knife being an article of such general utility and necessity the carriage of one constructed as here described involves the provision at the same time, and on almost all occasions, of a door-fastener, and this without adding materially to the bulk of the knife. Such a combined device will be found of great advantage to travellers and others.

What I claim as my invention, and desire to secure by Letters Patent, is—

A pocket-knife, provided with a pivoted or hinged screw, whereby it is made to subserve the purpose of a door-fastener, substantially as specified.

A. W. HALL.
